UNITED STATES PATENT OFFICE.

ANTON F. ENGLERTH, OF CHICAGO, ILLINOIS.

SANITARY TOOTHPICK RECEPTACLE.

Application filed February 9, 1922. Serial No. 535,249.

To all whom it may concern:

Be it known that I, ANTON F. ENGLERTH, a citizen of the United States, and a resident of Chicago, in the county of Cook and State 5 of Illinois, have invented certain new and useful Improvements in a Sanitary Toothpick Receptacle, of which the following, reference being had to the drawings accompanying and forming a part hereof, is

10 a specification.

This invention relates to receptacles wherein tooth picks, (or matches), may be stored, and which are designed to permit the removal of a pre-determined number or the 15 articles stored therein to be removed therefrom on a given operation of the device, by any person having access thereto.

Among the objects of the invention is to obtain a receptacle in which a large number 20 of tooth picks may be deposited and from which one or more, (as determined), may be easily obtained at any time, without the possibility of the person removing the permitted number thereof having access to or touching 25 the remainder of said tooth picks which are contained in the receptacle. An additional object is to obtain a receptacle wherein, when the supply of tooth picks contained therein is exhausted, an additional supply can be 30 readily placed therein. An additional object is to obtain a receptacle in which the tooth picks stored therein will not be liable to become displaced in a manner to prevent the delivery of the determined number which 35 are designed to be taken therefrom at a given operation of the device. An additional object is to obtain a device which is presentable in appearance, which may be placed upon a show case, table, counter or other 40 article; which is simple in construction, economically made, and not liable to be broken or to get out of order.

In the drawings referred to Fig. 1 is a front elevation of a device embodying the 45 invention, with a portion of the front side thereof removed, to exhibit certain operative parts to view.

Fig. 2 is a vertical section, on line 2—2 of Fig. 1, viewed in the direction indicated 50 by arrows.

Fig. 3 is a top plan view, with the cover of the shell of the device removed; and

Fig. 4 is a top plan view of a blank from 55 which a hanging door forming a member of the device, is obtained.

A reference character applied to designate

a given part indicates said part throughout the several figures of the drawing wherever the same appears.

A represents a base, and *a* a rectangular flange on the upper side of said base. B represents the shell or case of the device. C represents a cover on the upper open end of shell or case B, and is illustrated as attached thereto, as by hinge C' (Fig. 2). The lower end of shell B fits to the outside side of flange *a*, and is illustrated as secured thereto by the screws D, D. E represents an elevated portion of base A, which is provided with a curved front side. The elevated portion E of the base is for appearance, it being exposed to view through an opening in the lower part of the front side of shell B. F represents a receptacle, in which the articles desired to be stored, (to be taken out therefrom in the manner hereinafter described) are placed, before said receptacle is deposited in shell B. *f*, *f*, represent flanges on the sides of receptacle F, being there placed in position to be engageable with the grooves formed by turned over edges F', F', of plate *f*' said plate being illustrated as secured to the back face of the upper portion of the front of shell B. Said flanges and grooves hold the receptacle F in position in said shell B, and to remove the receptacle it is merely necessary to turn cover C back on its hinges and draw the receptacle upward out of the shell. G represents a cover which is positioned on the front side of receptacle F, when said receptacle is in position in shell B, and is maintained closed by the front of said shell, or by plate *f*' secured thereto as described. When the receptacle is removed from shell B, to have the supply of tooth picks therein replenished, said receptacle is preferably held so that cover G is on the upper side thereof. *g*' represents an inclined table which is secured to cover G, on the inner face thereof, and H, *h*, respectively represent inclined tables. Tables *g*', H, and *h*, are designed to prevent the tooth picks contained in receptacle F from becoming crossed so as not to be delivered as hereinafter set forth. I represents a hanging door, which is hinged on pintle J, at the lower end of the front side of receptacle, when said receptacle is in position in the shell B to be operated. The door I swings inwardly, to operate the device, and I', I', represent ears on the sides of receptacle F, said ears being

turned to an angle of about ninety degrees from said sides, to limit the outward movement of said door I, (see Fig. 1).

The door I is obtained from blank K, (Fig. 4), which is hinged on the pintle J by turning the parts lettered k, k, around said pintle. L represents the part of said blank which is turned at an angle to the remainder of said blank to obtain an inclined table, which is designated by said letter L in Fig. 2 of the drawings. The bottom M of receptacle F is inclined, when the receptacle is in place in shell B, and the part m of said bottom is curved on a radius which is centered on pintle J, and is in spaced relation to the free edge of door I, as said door is moved inwardly in operating the device. Part m of said bottom is illustrated as provided with a plurality of grooves N, n, which are sufficiently deep to contain the articles which are designed to be delivered from the receptacle at each operation thereof, and to permit the lower edge of said door to pass thereover. The front of shell B is cut away, as on lines O, O, Fig. 1, so that the door I is exposed to view and may be swung inwardly to beyond the grooves N, n, and P, (Fig. 2), represents a rod which forms a stop to limit the inward swing of said door.

The table formed by the front part m of the bottom of receptacle F is recessed, as at Q, (Fig. 3), so that when the door I is swung inwardly, as by placing the end of the fore finger or thumb of the person using the device and forcing said door inwardly, either said fore-finger or thumb will be underneath the tooth picks which are in said grooves N, n, and by closing said thumb and fore-finger thereon they may be removed from the device.

In the foregoing described operation, any tooth picks on the curved portion m of the bottom of the receptacle F, which are not contained in grooves N, n, will be forced back by the door I, the bottom edge of said door being close to but not in contact with said curved part m. On the turning inwardly of said door any tooth picks on the table L will be raised thereby, and room will be given for the tooth picks which are moved by the door I.

An additional function of the several tables g', H, h, and L, to that of maintaining the tooth picks in substantially parallel position, is to prevent the accumulation of a sufficient number of tooth picks back of door I to prevent its being forced inwardly when it is desired to operate the device and obtain a tooth pick therefrom, as described.

One of the grooves N, n is omitted from the part m of the bottom of receptacle F, when it is designed that but one tooth pick can be taken from the device at each operation thereof.

The device may be used for storing matches, if desired, and one or two matches, corresponding with the number of grooves in part m of the bottom of receptacle F, can be taken therefrom, in the same manner as tooth picks can be taken, as hereinbefore described.

I claim:

1. In a sanitary receptacle, a shell having the lower portion of one side thereof removed, in combination with a receptacle removably contained in said shell, said receptacle provided on one side thereof with a cover and with a hanging door, a portion of the bottom of said receptacle in spaced relation to and curved to correspond with the path of movement of the lower edge of said door and provided with grooves adapted to hold an article contained in said receptacle and to permit said door to pass thereover, and means to limit the swing of said door.

2. In a sanitary receptacle, a shell having the lower portion of one side thereof removed, and guide grooves on the inner face of the remainder of said side, in combination with a receptacle provided with flanges on the sides thereof arranged to co-act with said guide grooves, one of the sides of said receptacle provided with a cover and with a hanging door, a portion of the bottom of said receptacle curved in spaced relation with the path of movement of the lower edge of said door, and said curved portion of the bottom provided with grooves adapted to hold an article contained in said receptacle and to permit said door to pass thereover, and said curved portion of said bottom provided with a recess extending inwardly from the front edge thereof, and means to limit the swing of said door.

3. In a sanitary receptacle, a shell having the lower portion of one side thereof removed, in combination with a receptacle removably contained in said shell, one side of said receptacle open, a cover and a door hinged to said open side of said receptacle, and inclined tables in said receptacle, a portion of the bottom of said receptacle in spaced relation to and curved to correspond with the path of movement of the lower edge of said door and provided with grooves adapted to hold an article contained in said receptacle and to permit said door to pass thereover, and means to limit the swing of said door.

4. In a sanitary receptacle, a shell having the lower portion of one side thereof removed and guide grooves on the inner face of the remainder of said side, in combination with a receptacle, flanges on the sides of said receptacle arranged to co-act with said guide grooves, one of the sides of said receptacle open, a cover and a hanging door hinged on said open side to form a wall on said side, a

portion of the bottom of said receptacle curved in spaced relation to the path of movement of the lower edge of said door and extending through the open portion of 5 said side of the shell, and said curved portion of the bottom of the receptacle provided with a groove adapted to hold an article contained in the receptacle and permit the lower edge of said door to swing thereover, 10 and means to limit the swing of said door.

5. In a sanitary receptacle, a shell having the lower portion of one side thereof removed, in combination with a receptacle open on one side thereof, removably positioned in said shell, a cover on said open 15 side of said receptacle, and a door hinged

on said open side, means to limit the swing of said door, a portion of the bottom of said receptacle in spaced relation to and curved to correspond with the path of movement 20 of the lower edge of said door and arranged to extend through the open lower portion of one side of said shell, said curved portion of said bottom of the receptacle provided with a groove adapted to hold an article contained 25 in said receptacle and permit said door to pass thereover, and provided with a recess on the front edge thereof.

ANTON F. ENGLERTH.
